Primary Examiner — Susan Moon Lee

(74) Attorney, Agent, or Firm — QuickPatents, LLC;
Kevin Prince(57) **CLAIM**

I claim the ornamental design for a pet waste scooping tool, as shown and described.

DESCRIPTION

FIG. 1 is a front perspective view of a pet waste scooping tool, showing my new design in a partially open configuration;

FIG. 2 is a front perspective view thereof, illustrated in a closed configuration;

FIG. 3 is a rear perspective view of the pet waste scooping tool in its partially open configuration;

FIG. 4 is a front elevational view thereof;

FIG. 5 is a rear elevational view thereof;

FIG. 6 is a left-side elevational view thereof;

FIG. 7 is a right-side elevational view thereof;

FIG. 8 is a top plan view thereof; and,

FIG. 9 is a bottom plan view thereof.
